UNITED STATES PATENT OFFICE.

GEORGE B. CARLSON, OF CARVER, MINNESOTA.

EQUALIZING-BOLSTER.

1,290,081.

Specification of Letters Patent.

Patented Jan. 7, 1919.

Application filed March 20, 1918. Serial No. 223,594.

To all whom it may concern:

Be it known that I, GEORGE B. CARLSON, a citizen of the United States, residing at Carver, in the county of Carver and State 5 of Minnesota, have invented certain new and useful Improvements in Equalizing-Bolsters, of which the following is a specification.

The invention has relation to vehicle running gear, and more particularly to wagons 10 embodying bolsters and stakes for retaining the load in position, the purpose being the provision of a bolster which will equalize the load whether the latter is distributed uniformly or not.

15 The invention aims to provide for equalizing the load on the running gear which is of advantage when traveling over rough roads or surfaces, thereby insuring each of the supporting wheels carrying an equal 20 amount of the load and obviating undue strain upon any part of the running gear.

25 The invention consists of a bolster embodying relatively upper and lower members, an equalizer between such members, and yieldable connections whereby the weight of the load is imposed uniformly thereon and throughout the component parts comprising the bolster.

30 The drawing illustrates a preferred embodiment of the invention, however, it is to be understood that in adapting the same to meet different conditions, various changes in the form, proportion, and minor details 35 of construction may be resorted to without departing from the nature of the invention as claimed hereinafter.

In the drawings:

Figure 1 is a front view of an equalizing bolster embodying the invention, parts being broken away and parts in section.

40 Fig. 2 is a top plan view of the bolster.

Corresponding and like parts are referred to in the following description and indicated in both views of the drawings by like 45 reference characters.

The bolster comprises an upper member A and a lower member B, such members being spaced apart a proper distance and yieldably connected. The members A and B 50 comprise companion bars which are transversely spaced and disposed in parallel relation, the bars of each member being connected to operate in unison. The bars comprising the upper member A are shown most 55 clearly in Fig. 2 and are designated by the numeral 1, and the bars comprising the

lower member B are indicated in Fig. 1 by the numeral 2. Bolts or like fastenings 3 connect the bars 1 near their ends and like bolts or fastenings 4 similarly connect the 60 bars 2.

The equalizer comprises a plurality of bars pivotally connected at a central point by means of a fastening 5, the ends of the respective bars having a sliding connection 65 with the bolster members A and B. In the present instance, three bars are illustrated, the middle bar 6 being somewhat heavier than the side bars 7 because it is designed to carry as much of the load and sustain 70 an equal amount of the stress as the bars 7 combined. The three bars 6 and 7 are pivotally connected mid-way of their ends by a suitable fastening 5, and the ends of the middle bar 6 are slidably connected with 75 opposite ends of the bolster members A and B, as shown most clearly in Fig. 1. Opposite ends of the side bars 7 are slidably connected with opposite ends of the bolster members, as shown most clearly in Fig. 1. 80 The ends of the bars 6 and 7 are reinforced by means of plates 8. Other plates 9 reinforce the bars comprising the bolster members. The plates 8 and also the end portions of the bars 6 and 7 are formed with 85 longitudinal slots 10 which receive the fastenings or bolts 3 and 4 which connect the respective bars comprising the bolster members A and B. The construction is such as to maintain the bolster members A and 90 B in parallel relation at all adjustments, hence the load is equalized throughout the bolster.

The bolster members are yieldably connected and are guided in their relative vertical movements, and for this purpose, members 11 and 12 are secured to opposite end portions of the member A, and companion members 13 and 14 are connected to opposite ends of the bolster member B. These 100 members have a telescopic arrangement, *i. e.*, the members 13 and 14 are slidable within the respective members 11 and 12. The members 11 and 12 are tubular and constitute in effect bolster stakes. The members 105 13 and 14 preferably consist of end portions of a rod which is doubled upon itself into U-shape and secured at its lower or closed end between the bars 2 comprising the bolster member B. The members 11 and 12 are 110 secured at their lower ends between the bars 1 of the bolster member A. Expansible coil

springs 15 are disposed within the tubular members 11 and 12 and are confined between the coöperating telescoping members so as to sustain the load. Blocks 16 are secured 5 within the tubular members 11 and 12 by fastenings 17. These blocks sustain the vertical thrust of the springs 15. Pins 18 are supported in the upper ends of the members 13 and 14 and receive the lower ends of the 10 spring 15 and sustain the thrust thereon.

The coöperating members 11—13 and 12—14 act as guides and also as means for utilizing the tension of the springs 15 as 15 means for yieldably supporting the load. It is also noted that the members 11 and 12 act in the capacity of stakes to retain the load upon the bolster. The equalizing bars 6 and 7 being connected to the bolster members in the manner stated, serve in conjunction with 20 the telescopic connections at the ends of the members A and B to cause the latter to maintain a parallel position at all stages of their relative adjustment due to load and stress. The yieldable connections besides equalizing 25 the load also serve to neutralize shock incident to the vehicle passing over obstructions, or dropping into ruts or depressions.

What I claim is:

30 1. A bolster comprising upper and lower members, a tubular stake attached to each

end of the upper member, and constituting a standard for the bolster, a guide member attached to each end of the lower member and telescoping with the tubular stake, an expandable helical spring within the tubular stake 35 and confined between it and the telescoping guide member, and crossing bars pivotally connected at the point of crossing and having their ends slidably connected with the bolster members.

2. An equalizing bolster, comprising upper and lower members, each member comprising transversely spaced bars, tubular members secured between the ends of the upper bars and constituting guides and standards for the bolster, rods secured between the ends of the lower bars and telescoping with the tubular members, springs within the tubular members interposed between them and the rods to sustain the load, and crossing equalizing bars pivoted at their point of crossing and having their ends pivoted between the ends of the bars constituting the upper and lower bolster members.

50 In testimony whereof I affix my signature in presence of two witnesses.

55 GEORGE B. CARLSON.
